ATTORNEY

UNITED STATES PATENT OFFICE

146,932

DESIGN FOR A WHEELED HOBBYHORSE

Lawrence Wenpetren, Detroit, Mich.

Application April 27, 1946, Serial No. 129,033

Term of patent 7 years

(Cl. D14—14)

To all whom it may concern:

Be it known that I, Lawrence Wenpetren, a citizen of the United States and a resident of the city of Detroit, county of Wayne, and State of Michigan, have invented a new, original, and ornamental Design for a Wheeled Hobbyhorse, of which the following is a specification, reference being had to the accompanying drawings, forming a part thereof.

Fig. 1 is a top plan view of a wheeled hobby horse showing my new design;

Fig. 2 is a side elevation thereof;

Fig. 3 is a front elevational view thereof.

I claim:

The ornamental design for a wheeled hobbyhorse, as shown.

LAWRENCE WENPETREN.
